MATTRESS OR THE LIKE

Edwin L. Pabst, Cincinnati, Ohio, assignor to
 Spring-Air Company, Holland, Mich., a corporation of Michigan

Application January 10, 1944, Serial No. 517,697

7 Claims. (Cl. 5—359)

1

The present invention relates to cushion pad structures such as mattresses and the like and comprises an improvement in the construction described and claimed in my copending United States patent application Serial No. 472,511, filed January 15, 1943, issued April 3, 1945, as Patent No. 2,373,047.

The structure to which the invention relates is the type in which an outer casing, such as a mattress ticking, is compartmented by spaced parallel partition sheets extending between and secured to the top and bottom panel sheets, generally crosswise of the assembly, with resilient material such as cotton, hair, rubber or the like filling the compartments. Patent No. 2,373,047 describes and claims certain improvements in the relative arrangement of the outer casing and the inner partition sheets, and in the method of assembly. The present invention introduces further improvements which may be combined with those of the earlier application or may be used independently thereof.

Important objects of the present invention are to reduce the cost of manufacture of cushion pads of the type indicated, to strengthen the construction, to render it more durable in use, and to eliminate puckering and unevenness in the newly made product as well as the tendency to become puckered and uneven due to stretching of the fabric after a period of use.

The foregoing and other objects and advantages will be apparent to those skilled in the art from the following specification, taken in conjunction with the appended drawing, in which I disclose a preferred form of embodiment of the invention. It is to be understood that this embodiment is selected merely to illustrate the invention in a form which I now prefer and have found eminently satisfactory in actual practice. This disclosure is not to be taken as limiting the inventive features to the precise form in which they are disclosed. On the contrary, these features are susceptible of modification within the broad spirit of the invention as defined by the appended claims; moreover the novel features need not be used in the combinations in which they are embodied in the illustrated form, since some of them are capable of independent use.

In the accompanying drawing.

Figure 1 is a top plan view, broken away for economy of space, of a top or bottom mattress panel sheet showing the lines along which the sheet is folded to introduce the tucks which form an important feature of the invention;

Fig. 2 is a similar view of the sheet after the

stitching operation by which the tucks are formed;

Fig. 3 is a similar view showing the panel sheet after the partition sheets are sewed to the tucks;

Fig. 4 is a detail view showing an end portion of one of the tucks in side elevation;

Fig. 5 is a fragmentary perspective view of an assembly of top and bottom panel sheets showing the spaced relation in the finished product;

Fig. 6 is a cross sectional view of one side portion of a mattress showing the complete assembly of top and bottom panel sheets, a partition sheet and a side wall sheet;

Fig. 7 is a similar view showing the side wall panel sheet and partition sheet connected in a different manner from that shown in Fig. 6;

Fig. 8 is a perspective view of a finished mattress; and

Fig. 9 is a detail cross sectional view taken on the line 9—9 of Fig. 8.

Referring now to the drawing, where the invention is shown disclosed in a bed mattress, Fig. 1 shows a panel sheet 10 which is rectangular in shape and made of any durable fabric as is usual in the making of mattress ticking. Two of these panel sheets are used, one for the top of the mattress and one for the bottom. The sheet 10 in Fig. 1 may be considered to be the top sheet and it differs from the corresponding sheet shown in my Patent No. 2,373,047 only by being about two inches longer for incorporation in a finished mattress of the same size as the one shown in that patent. This extra length is necessitated by the provision of spaced parallel tucks, preferably arranged transversely of the sheet, to provide attaching surfaces for compartment partition sheets as will now be described.

In Fig. 1 the numerals 11, 11 indicate lines, which may be and preferably are imaginary lines, 40 along which the sheet is folded to provide the tucks 12 (Figs. 4 and 5). The line 13 in Fig. 1 indicates the juncture of the two plies which constitute the tuck, this line appearing also in Fig. 5. It will be understood that Fig. 1 depicts the unfolded blank, while Fig. 2 shows the finished blank with the tucks incorporated in it by a line of stitching 14 at the base of each tuck, securing the two plies together.

Fig. 3 shows the finished sheet with the margins 50 of the partition sheets 15 sewed by a lap seam to the flanges or ribs provided by the tucks 12. This connection is made by a line of stitching 16 spaced to be slightly inwardly of the line of stitching 14 which formed the tucking relationship of

the two plies.

The tucked sheet will be found reduced from its originally excess length to the length of the desired mattress, the excess material being used in the tucks. The partition sheets are sewed to the tucks and the edges of the sheet are then sewed to end and side wall sheets 17, 18 respectively to form a finished box structure having compartments defined by adjacent partition sheets adapted to be stuffed with any conventional filling. The end portions of the partition sheets 15 may be notched out, as shown at 19 and as disclosed in Patent No. 2,373,047, for the purposes there fully explained. When the mattress is filled and sewed closed the product will be found to be unusually durable and substantial because the top and bottom panel sheets present no lines of surface stitching where the partition sheets are connected to them. The connecting lines of stitching 16 are concealed within the structure, as best appears in Fig. 9, and being thus concealed they are protected from injury. The lines of stitching 14 which fix the tucks are likewise concealed within the structure so that they too are protected from damage. The assembling operation is greatly facilitated because it is much easier to sew the margins of the partition sheets 15 to the ribs formed by the tucks 12 than to perform the type of sewing shown in this part of the structure as disclosed in Patent No. 2,373,047 and as previously practiced. Moreover, it is easier to place properly the tucks in a blank flat sheet than to sew the partition sheets along straight and equally spaced parallel lines in a sheet of mattress ticking.

In addition to the foregoing advantages, the double plies of the tucks provide strengthening ribs which tend to maintain the mattress against distortion resulting from stretching of the mattress.

The structure is thus more readily made and is stronger and more durable in use than any conventionally made prior art device with which I am acquainted. Constructed as thus far described the invention obviously has considerable merit and novelty, but I prefer to introduce certain further improvements which are productive of additional advantages. These will now be described.

I prefer to deepen the tucks 12 along the end portions of each, i. e., along the side marginal zones of the mattress, as shown at 20 in Figs. 5 and 6. When the partition sheets 15 are notched at their corners as is preferred, these deepened or widened portions of the tucks extend into the cut out areas 19. They are not joined to the partition sheets, but they have the effect of taking up excess material from the length of the panel sheets so that the original overall length of the side marginal zones of the panel sheets is less than that of the intermediate zone thereof. I have attempted in Figs. 2 and 3 to illustrate the effect by the stippling 21. The arrangement permits a predetermined degree of crowning of the intermediate zone of each panel sheet resulting from the fact that the partition sheets 15 hold the intermediate zone down or inwardly of the mattress. There is less crowning, or none at all, along the side marginal zones of the mattress, where the material is not held down or inwardly by the partition sheets. If it were not for the deepened or widened tuck portions 20 in these side marginal zones the panel material would pucker. The material is however kept straight and flat by the novel arrangement of deepening the tucks because the excess material is thereby

removed from the plane of the panel sheet and tucked inwardly of the structure.

The effect is sought to be illustrated in Fig. 8, where it will be observed that the intermediate area of the mattress is well crowned as is desirable in these constructions, while the side marginal zones taper down to an edge which is quite flat and straight. This formation of the edge adapts it to receive very neatly the side and end wall sheets which are conventionally secured in place by usual border trimming or cording 22.

The end edges of each partition sheet 15 may be connected to the side wall sheets 18 in the conventional manner, as shown in Patent No. 2,373,047 and in Fig. 6 of the present application. However, I prefer to make this connection in the same general way as the connection between the side margins of the partition sheets 15 and the panel sheets 10, i. e., by the use of tucks. This arrangement is shown in Fig. 7, where it will be noted tucks 23 are sewed into each side wall sheet 18a with widened or deepened end portions and the intermediate portions are stitched to the end margins of the partition sheets. By deepening the end portions puckering of the margins of the side wall sheets is eliminated, and the use of tucks affords a strong, durable and easily made connection for the partition sheets and the side wall sheets.

The mattress may be trimmed in any desirable way and adoption of the process of the present invention, in the whole combination or any part of it, will be found to be productive of the advantages hereinabove asserted and to militate in no way against the incorporation of any conventional features or constructions for any utilitarian or ornamental purposes.

I claim:

1. A cushion pad structure such as a mattress or the like comprising substantially rectangular top and bottom panel sheets, a plurality of inwardly projecting spaced parallel tucks sewed into said sheets and extending substantially entirely across the pad, partition sheets sewed at their opposite margins to opposed pairs of said tucks, and filling disposed in the compartments defined by adjacent partition sheets, the portions of said tucks in the side marginal zones of the structure being wider than the portions in the intermediate zone whereby the structure is more highly crowned in its intermediate zone than along its edges.
2. A substantially rectangular panel sheet for use as the top or bottom surface wall of a cushion pad structure such as a mattress or the like, said sheet having a plurality of spaced parallel tucks sewed into it substantially entirely across its width forming inwardly projecting ribs or flanges to which filling compartment partition sheets may be sewed, said tucks being wider along the marginal zones of the sheet than in the intermediate zone whereby the pressure of filling in a structure made from said sheet will cause the sheet to be more highly crowned along its intermediate zone than along its edges.
3. A cushion pad structure such as a mattress or the like comprising substantially rectangular top and bottom panel sheets, a plurality of inwardly projecting spaced parallel tucks sewed into said sheets and extending across the pad, partition sheets sewed at their opposite margins to the intermediate portions only of opposed pairs of said tucks and being unconnected to the tucks in the side marginal zones of the structure, and filling disposed in the compartments defined by adjacent partition sheets, said tucks being wider

in said side marginal zones than in said intermediate portions whereby the structure is more highly crowned in its intermediate zone than along its edges and said side marginal zones are substantially coextensive in overall length with said intermediate zone.

4. A cushion pad structure such as a mattress or the like comprising substantially rectangular top and bottom panel sheets, means connecting said sheets to provide a plurality of parallel compartments, filling in said compartments, a series of tucks sewed into the sheets to which tucks said connecting means are sewed, said tucks extending substantially entirely across each sheet and extending to a greater depth across the side marginal zones than across the intermediate zone of each sheet whereby the intermediate zone of the sheet is more highly crowned than the side marginal zones.

5. A cushion pad structure such as a mattress or the like comprising top and bottom panel sheets and end and side wall sheets connecting the panel sheets to form a box ticking, partition sheets arranged in spaced parallelism across the structure and having their corners notched out and their end edges connected to the side wall sheets, a plurality of inwardly projecting spaced parallel tucks sewed into the panel sheets and extending across the pad to provide inwardly extending ribs or flanges, means connecting the side margins of each partition sheet between the notched out corners thereof to opposed pairs of said tucks, and filling disposed in the compartments defined by adjacent partition sheets, said tucks being relatively narrow throughout the portions thereof which are connected to the partition sheets and being relatively wide throughout the portions thereof which extend into the notched out corners of the partition sheets, whereby the intermediate zones of the tucked panel sheets are originally longer than the marginal zones thereof but both zones are substantially coextensive in length in the finished structure due to the crowning of the intermediate zone resulting from expansive pressure of the filling.

6. A cushion pad structure such as a mattress or the like comprising top and bottom panel sheets and end and side wall sheets connecting the panel sheets to form a box ticking, partition sheets arranged in spaced parallelism across the structure and having their corners notched out, a plurality of inwardly projecting spaced parallel tucks sewed into the panel sheets and into the side wall sheets and extending across the pad and down the sides of the pad to provide inwardly extending ribs or flanges, means connecting the side margins of each partition sheet between the notched out corners thereof to opposed pairs of the tucks in the panel sheets, means connecting the end edges of each partition sheet to opposed pairs of the tucks in the side wall sheets, and filling disposed in the compartments defined by adjacent partition sheets, said panel sheet tucks

being relatively narrow throughout the portions thereof which are connected to the partition sheets and being relatively wide throughout the portions thereof which extend into the notched out corners of the partition sheets, whereby the intermediate zones of the tucked panel sheets are originally longer than the marginal zones thereof but both zones are substantially coextensive in length in the finished structure due to the crowning of the intermediate zone resulting from expansive pressure of the filling.

7. A cushion pad structure such as a mattress or the like comprising top and bottom panel sheets and end and side wall sheets connecting the panel sheets to form a box ticking, partition sheets arranged in spaced parallelism across the structure and having their corners notched out, a plurality of inwardly projecting spaced parallel tucks sewed into the panel sheets and into the side wall sheets and extending across the pad and down the sides of the pad to provide inwardly extending ribs or flanges, means connecting the side margins of each partition sheet between the notched out corners thereof to opposed pairs of the tucks in the panel sheets, and extending across the pad and down the sides of the pad to provide inwardly extending ribs or flanges, means connecting the end edges of each partition sheet to opposed pairs of the tucks in the side wall sheets, and filling disposed in the compartments defined by adjacent partition sheets, said tucks being relatively narrow throughout the portions thereof which are connected to the partition sheets and being relatively wide throughout the portions thereof which extend into the notched out corners of the partition sheets, whereby the intermediate zones of the tucked panel and side wall sheets are originally longer than the marginal zones thereof but both zones are substantially coextensive in the finished product due to the crowning of each intermediate zone resulting from expansive pressure of the filling.
